UNITED STATES PATENT OFFICE.

FREDERICK C. FENELEY, OF DETROIT, MICHIGAN.

PEN.

1,094,138.

Specification of Letters Patent. Patented Apr. 21, 1914.

Application filed November 17, 1913. Serial No. 801,470.

To all whom it may concern

Be it known that I, FREDERICK C. FENELEY, a citizen of the United States of America, residing at Detroit, in the county 5 of Wayne and State of Michigan, have invented certain new and useful Improvements in Pens, of which the following is a specification, reference being had therein to the accompanying drawings.

10 This invention relates to pens of that type commonly styled "fountain pens," and the primary object of my invention is to provide a pen that can be advantageously used for writing or printing signs, marking goods or packing cases, or for producing heavy lettering or writing of various styles.

15 Another object of this invention is to provide a fountain pen having a reservoir for ink or other writing fluid, and which is provided with yieldable means for feeding ink in sufficient quantities to the writing or printing point or member of the pen.

20 A further object of this invention is to provide a simple, durable and inexpensive pen of the above type wherein a yieldable writing or printing member provides a plurality of ink bearing surfaces which permits of stripes or marks of various widths being made with the pen, the width of a stripe 25 being defined by the width of a face of the member and the maximum width of a stripe by the distance between the angles of said faces.

25 I attain the above and other objects by a mechanical construction that will be herein-after specifically described and then claimed, and reference will now be had to the drawing, wherein—

30 Figure 1 is a perspective view of the pen; Fig. 2 is a longitudinal sectional view of the same; Fig. 3 is a view of the outer end of the pen, and Fig. 4 is a detail elevation of the writing point or member.

35 A pen in accordance with this invention 40 comprises a cylindrical hollow body or tube 1 constituting the handle and reservoir of the pen. The outer end of the body 1 is reduced or contracted to provide a frusto-pyramidal extremity having flat tapering side walls 2, the inner walls of the extremity 45 providing a socket or seat 3, the purpose of which will presently appear. The outer end or extremity of the body 1 is beveled, as at 4, the bevel extending inwardly from the

5 top side of the extremity to the bottom side thereof, the bevel or inclination being such that when the pen is held in the hand at an angle to a surface to be written or printed upon, the beveled end of the extremity engages the surface with all its points of contact in a common plane.

55 The walls 2 are longitudinally slotted or slotted, as at 5, the slits or slots being equally spaced and extending from the outer edges of the walls inwardly to provide a plurality 60 of equally spaced ink bearing points 6 and it is in this connection that the slits or slots 5 serve practically the same purpose as the slots and slits of an ordinary pen point.

65 Arranged in the body 1 and normally engaging the seat 3 is a yieldable writing point or member 7 which serves two purposes, namely, as an ink feeding device when the pen is in use and as a closure for the extremity of the body 1 when the pen is not 70 in use. The member 7 preferably comprises a cylindrical body of less diameter than the bore of the body or tube 1, thereby providing an annular space 8 which permits of ink or writing fluid flowing toward the seat 3 of 75 the body 1. The outer end of the member is reduced or contracted to provide flat tapering walls 9 adapted to engage the walls of the seat 3 and the tapering end of said member is of sufficient length to protrude 80 from the beveled extremity 2. The outer end of the member 7 is beveled, as at 10, in a plane in parallelism with the beveled end of the extremity and the beveled end of said member has a recess 11 providing walls 12 85 that are similar to the walls of the extremity 2. The outer edges of the walls 12 are slotted or slotted, as at 13, to provide a plurality of ink bearing points 14, the slits or slots 13 registering with the slits or slots 5 90 of the extremity 2, when the member 7 is shifted inwardly as pressure is brought to bear upon the printing end of the pen. The walls of the member 7 are slightly flared, as exaggerated in the drawing, whereby the 100 slotted outer edges of the walls 12 will be carried into close proximity to the walls of the extremity 2, thus reducing the end of the ink passage between said member and the extremity, whereby just a sufficient quantity of ink will be supplied to the ink bearing points of the pen.

105 Suitably connected to the inner end of the

member 7, as at 15, is a coiled compression spring 16 which is arranged longitudinally of the body, the combined length of said spring and the member being greater than the length of the body 1, whereby when a cap 17 is screwed or otherwise mounted upon the inner end of the body 1, the spring 16 is placed under tension to hold the member 7 normally seated in the extremity of the body 1. The inner end of the body 1 is externally screw threaded, as at 18, to accommodate the cap 17 and by removing said cap the body 1 can be easily filled with ink or other writing or printing fluid.

In operation, pressure brought to bear upon the writing or printing end of the pen causes the member 7 to yield, thereby establishing a passage between the walls 9 of the member 7 and the walls of the extremity of the body 1, permitting ink to flow toward the ink bearing points 6 and 14. Ink is fed to these points through the medium of the slits or slots 5 and 13 and as the pen is moved over a surface a broad stripe or mark is made, as shown in Fig. 1. In making a plus mark the intersecting lines are of the same width and in making a cross mark without changing the position of the pen, the intersecting lines are of a greater width than the intersecting lines of the plus mark. The width of the plus mark line corresponds to the distance between opposite sides of the writing or printing points and the width of the cross lines corresponds to the distance between the angles of the walls of the writing point. In practice, it is not necessary to completely force the outer end of the member 7 into the extremity of the body 1, as the outer end of the member 7 can be used for writing or printing purposes without bringing the end of the extremity into engagement with the surface to be written or printed upon. A slight pressure upon the pen provides sufficient space between the member 7 and the extremity of the body for ink to flow onto the ink bearing points 14. Immediately upon the writing or printing points of the pen being removed from a surface the spring 16 causes the member 7 to engage the seat 3 thereby shutting off the flow of ink.

When the cap 17 is removed from the inner end of the body 1, the end of the spring 16 protrudes from the body, thus permitting of the same being gripped and the member 7 removed from the body, whereby the body can be flushed and thoroughly cleansed. Of course, the member 7 when removed from the body can be similarly treated.

The pen in its entirety can be made of a non-corrodible material and of such sizes as to be conveniently used for various purposes.

One embodiment of my invention has been illustrated, but it is to be understood

that the structural elements are susceptible to such variations and modifications as fall within the scope of the appended claims.

What I claim is:

1. A pen comprising a body having an extremity thereof provided with ink bearing points, and a member normally seated in the extremity of said body and having ink bearing points adapted to register with the ink bearing points of the extremity of said body. 70

2. A pen comprising a hollow body having an extremity thereof provided with ink bearing points, a member normally seated in the extremity of said body and having ink bearing points protruding beyond the 80 ink bearing points of said extremity, and means within said hollow body for retaining said member normally seated in the extremity thereof.

3. A pen comprising a hollow body constituting a reservoir, said body having an extremity thereof beveled and provided with ink bearing points, and a member normally seated in the extremity of said body and having a beveled end projecting from 90 the beveled end of said extremity and provided with ink bearing points adapted to register with the ink bearing points of said extremity when said member is unseated. 85

4. A pen comprising a body having a 95 frusto-pyramidal shaped extremity provided with ink bearing points and a correspondingly shaped yieldable closure normally seated in the extremity of said body and provided with ink bearing points. 100

5. A pen comprising a hollow body constituting a reservoir, said body having a reduced beveled extremity, a recessed yieldable member normally seated in the extremity of said body and having a beveled end 105 adapted to be shifted into the plane of the beveled end of the extremity of said body.

6. A pen comprising a hollow body constituting a reservoir, said body having a reduced beveled extremity, a recessed yieldable member normally seated in the extremity of said body and having a beveled end adapted to be shifted into the plane of the beveled end of the extremity of said body, and means longitudinally of said body for 115 holding said member normally seated and to facilitate the removal of said member from said body.

7. A pen comprising a hollow body having a reduced end provided with opposed ink bearing points, and a yieldable member normally seated in the reduced end of said body and having opposed ink bearing points adapted to be shifted to and from the ink bearing points of the reduced end of said 125 body.

8. A pen comprising a hollow body constituting a reservoir, said body having an extremity thereof beveled and provided with slotted edges, and a yieldable member 130

arranged in said body and having a beveled slitted end adapted to be moved to and from the slitted extremity of said body.

9. A pen comprising a hollow body constituting a reservoir, said body having an extremity thereof beveled and provided with slitted edges, and a yieldable member arranged in said body and having a beveled slitted end adapted to be moved to and from the slitted extremity of said body, and means arranged within said body for holding said member normally seated in the extremity of said body to close the same.

10. A pen comprising a hollow body having an end thereof beveled and slitted, a member movably mounted in the end of said body and having a beveled and slitted end

normally protruding from the end of said body.

11. A pen comprising a hollow body having an end thereof beveled and slitted, and a member movably mounted in the end of said body and having a beveled and slitted end normally protruding from the end of said body, and means within said body and co-operating therewith in holding said member whereby the end of said body is normally closed.

In testimony whereof I affix my signature in presence of two witnesses.

FREDERICK C. FENELEY.
